UNITED STATES PATENT OFFICE.

HARVEY G. COFFMAN, OF WASHINGTON COURT-HOUSE, OHIO.

PAPER-FILE.

SPECIFICATION forming part of Letters Patent No. 436,214, dated September 9, 1890.

Application filed May 9, 1890. Serial No. 351,150. (No model.)

To all whom it may concern:

Be it known that I, HARVEY G. COFFMAN, a citizen of the United States, and a resident of Washington Court-House, in the county of Fayette and State of Ohio, have invented certain new and useful Improvements in Paper-Files, of which the following is a specification.

My invention relates to files for holding letters, circulars, bills, tablets, or other articles in a box, having a follower adapted to be clamped so as to press and hold the papers in position, all of which will be fully set forth in the description of the accompanying drawings, making a part of this specification, in which—

Figure 1 is a side elevation of my improvement. Fig. 2 is a section on line xx , Fig. 1. Fig. 3 is a top plan view of the clamp shown in Fig. 1. Fig. 4 is an end elevation of a modified form. Fig. 5 is a central longitudinal section of Fig. 4.

A represents the base of the file-box, and B the stationary end.

C represents two side rods, upon which the follower slides.

D represents a sleeve provided with tubular collars a at either end, which form journals for the sleeve D to move upon. These tubular collars are cut away inside of the sleeve on the inner side, as shown at E, Fig. 2, so as to allow the sleeve D to be clamped to the rods by mechanism on the interior of said sleeve. I have shown two forms of interior clamping mechanism.

35 In Fig. 2, I represent locking-bars, the inner ends of which are inclined so as to be acted upon by the wedge F. This wedge is provided with a thumb b , as shown in Fig. 1, so as to operate rapidly.

40 d represents a stationary arm rigidly secured to the sleeve D, and provided with ears e to which the handle of the wedge F is pivoted.

45 g represents a spring for holding the wedge F normally down so as to force the locking rods I outward against the bars C.

50 L represents a semicircular bracket, the ends of which are rigidly secured to the follower K. It passes around the sleeve D and rigidly attaches the same to said follower.

In the modification in Figs. 4 and 5, instead of locking-bars I, I provide a vibratory sleeve

O. On the ends of said sleeve O are formed cams N.

P represents a knob secured to sleeve O, 55 projecting up through the slot in the sleeve D above the handle d . The operator grasps the handle d and turns the knob P to rotate the cam-sleeve O, so as to force it against the carrying-rods or release it therefrom. 60

The mode of operation is as follows: The operator takes hold of the handle d and releases the clamp, and the follower K is allowed to slide freely back and forth upon the ways C. The clamp is operated to lock it in any desired position. This form of follower and clamp possesses many advantages over those hitherto used. The follower K is rigidly secured upon the bars C, so that any desired amount of compression may be put upon the 70 article held between the follower K and the stationary end B. It is subjected to little or no lost motion and is not liable to get out of order.

The tubular sleeve D is a very important 75 feature of my invention, as it forms a lateral brace to incline ways C and furnishes means for carrying the locking device within the same so as to lock the sleeve D to the ways C by a device carried inside of said sleeve. 80 The ways C are thus stiffened against outward or inward strains, and they are clamped in any desired position without strain upon the ways, which are preferably made of wire, so as to be light, and are therefore liable to 85 be bent or injured unless so braced and supported.

Having described my invention, what I claim, is—

1. In a paper-file, the combination, with a 90 base A, an end B, a horizontal rod C, and a follower K, of a slotted sleeve D, secured to the follower and having a bearing sliding on the rod to move the sleeve lengthwise thereupon, and a clamp mechanism for rigidly locking the sleeve and its bearing at any point along the length of the rod, substantially as described. 95

2. In a paper-file, the combination of the follower K, rigidly secured to the sleeve D, 100 provided with tubular bearings a , in combination with the locking-bars I and the wedge F, substantially as herein specified.

3. In a paper-file, the follower K, supported

upon the sleeve D, rigidly secured thereto, and provided with tubular bearings *a* and handle *d*, secured centrally to said sleeve, and the clamping-wedge F, pivoted thereto, substantially as specified.

4. In a paper-file, the follower K, journaled upon the moving ways C by means of the sleeve D, and handle *d*, rigidly attached to said sleeve, and means for operating a lock-

ing device carried within said sleeve projecting up through the same above said handle *d*, substantially as described.

In testimony whereof I have hereunto set my hand.

HARVEY G. COFFMAN.
